UNITED STATES PATENT OFFICE.

JULIAN A. CAMPBELL, OF LONG BEACH, CALIFORNIA.

DEPHLEGMATOR.

Application filed July 30, 1925. Serial No. 46,972.

This invention has to do with devices commonly known as dephlegmators, whose function is to separate the liquid or condensate, or condensable vapors from gases or vapors. Such apparatus is used for the separation of liquids or condensates carried in or along with uncondensed vapors and gases, in operations upon petroleum oils. Such operations are sometimes carried on in distillation or cracking treatment of petroleum oils, and sometimes, for instance, in processes for obtaining light hydro-carbons from natural gas. The particular dephlegmator herein shown and described has been designed specifically in connection with a plant for recovering light hydro-carbons such as gasoline from casing-head gas; but it will be understood that such use is not a limitation upon the apparatus and that the apparatus may be put to other uses as desired; in fact, such specific use involves no different functions as over other uses. It is a general object of the invention to provide a very simple form of dephlegmator in which a mixed body of gases and vapors may be subjected to a comparatively slow cooling that is as perfectly gradual and uniform as possible; the substances being handled in such a way that the liquid condensate may settle and stratify out of the uncondensed vapors and gases and may then be completely and cleanly separated from those uncondensed parts. A great deal of the uncondensable products in such a mixture is carried either in vaporous form or in finely divided or atomized suspension; and agitation is to be avoided because such agitation will cause the uncondensed vapors and gases to pick up and carry off a part of the liquid. It is, therefore, an object of my invention to avoid agitation as far as possible, to provide a dephlegmator apparatus in which the flow of the various gases, vapors and liquids is smooth and undisturbed; with the result that the condensate is thoroughly and cleanly separated from the uncondensed vapors and gases.

For the purpose of explaining my invention, I will assume that a mixed body of vapors and gases (most such bodies contain some fixed gases) is delivered to the dephlegmator apparatus at a temperature substantially high enough to keep all the condensable vapors in vapor form. I shall then explain how my dephlegmator appa-

ratus cools the mixed body and so handles the condensate and gases or uncondensed vapors in such a manner as to cleanly separate all condensate, whether in liquid form or in the form of mist. For this purpose I illustrate in the accompanying drawings a preferred and specific embodiment that is illustrative of the invention, reference for this purpose being had to the accompanying drawings, in which:

Fig. 1 is a plan of the dephlegmator apparatus;

Fig. 2 is a fragmentary side elevation thereof;

Fig. 3 is a fragmentary enlarged plan;

Fig. 4 is a fragmentary enlarged horizontal section on line 4—4 of Fig. 2; and

Fig. 5 is a vertical longitudinal section on line 5—5 of Fig. 4.

Although I here give a description in full detail of this specific and preferred embodiment of my invention, it will be understood that this is not done for the purpose of limiting the invention except as may be expressly stated in the following claims; but that I give this description in detail so that others may understand the invention itself through having a complete understanding of one form of the invention.

A flat and relatively shallow trough 10 is provided with a central partition 11 that extends from one end 12 of the trough to a point somewhat short of the other end 13. At end 12 there are two pipe headers 14 and 15 into which several circulation pipes 16 are connected; header 14 forming an entry head for the pipes and header 15 a delivery head for them. The circulation pipes 16 lie horizontally in the trough, somewhat above its bottom and supported at intervals upon suitable supports 17, so that the cooling water that flows in the trough may come into contact with the pipes completely around them. The pipes extend from header 14 to points near end 13 of the trough and then turning across the end extend back the whole length of the trough to header 15.

The mixed vapors and gases are delivered to header 14 through pipe 20 and flow through the circulation pipes 16 around through the trough and back to header 15, thus having a total flow of approximately twice the length of the trough. Cooling water is introduced to the trough through

a pipe 21 at or near delivery header 15 and this cooling water flows to the far end of the trough at one side of partition 11 and then flows back toward the other end at the 5 opposite side of the partition. The trough is set preferably substantially level so that when the device is in operation there is always in the trough a body of water covering the circulation pipes. In the form and 10 arrangement of apparatus here shown, I use no outlet for the water, the water being dissipated by evaporation, chiefly at and around the hotter ends of the pipes where the hot vapors and gases are first introduced. This zone of largest evaporation is 15 at the place substantially furthest removed from the point of introduction of water, so that the removal of water by evaporation and the constant addition of water through 20 pipe 21 causes a slow and very uniform flow of the water in a direction opposite to the flow of gases and vapors. The cooling water is, therefore, always hottest at the point where the gases and vapors are first 25 introduced; and due to its very gradual and uniform flow the water temperature is uniformly graduated between these two points. Consequently the temperature of the vapors, etc., in the circulation pipes, they flowing 30 uniformly through these pipes, is highest at the point of first introduction, lowest near the delivery header 15 and is very uniformly graduated between these two extreme temperatures, cooling taking place with the 35 greatest possible uniformity.

The mixed vapors and gases that are introduced at header 14 may be uniformly distributed between the several circulation pipes 16 if the apparatus is working at full 40 capacity; or if it is desired to work the apparatus at less than full capacity, at least some of the pipes 16 may be provided with valves 16^a so that some of the pipes may be cut off. At whatever capacity the apparatus is working, it is desired that the flow 45 of vapors, etc., through the circulation pipes shall be comparatively slow so as to avoid as far as possible all agitation. Also it will be noted that circulation pipes 16 are so arranged that when the condensate is gradually formed in the pipes, it will drop to the bottom of each pipe and flow undisturbed along its bottom to the end of the pipe. There are no vertical turns, coils, or 55 the like in these pipes that tend to remix the condensate with the uncondensed vapors and gases once the condensate is dropped out. Consequently as the gases and vapors move 60 through the pipes and are gradually and uniformly cooled, the condensate is gradually dropped out of the vapors and gases and flows in increasing quantity along the bottoms of the pipes; and when the two parallel streams of condensate and gases and 65 vapors in each pipe reach header 15, they

move smoothly and evenly into the header, the condensate occupying the lower portion of that header and the gases and vapors the upper portion.

The temperatures at which the gases, 70 vapors and condensate are delivered into final header 15 will depend upon various factors, among which are the temperatures at which the gases and vapors are delivered to initial header 14, the time period during 75 which the gases and vapors traverse the circulation pipes, and the amount of water continuously supplied to the water feed end of the device. Water may, of course, be fed fast enough to more than supply the water 80 evaporated, with the result that the pan may be constantly overflowing. In this way lower final temperatures may be attained; but I find in the usual cases that a water supply such as will just about offset the 85 water evaporation is sufficient to obtain the temperature desired. The temperature at the final header 15 will, of course, always be at or below normal water boiling point. 90

From what I have said it will be apparent 95 that when the gas and liquid are delivered into final header 15 the condensate will occupy the lower part of the header without being agitated into admixture with the gases and uncondensed vapors. The exact nature of the condensate will, of course, depend upon the temperature maintained at header 15; but whatever that temperature may be, by far the larger part of the matter condensable at that temperature passes into 100 and through the header in liquid form. Very little of the condensable matter is carried by the gases and uncondensed vapors in the form of mist.

The outlet pipe 25 that leads from header 105 15 to separator 26 preferably leads from the bottom of header 15 as is shown in Fig. 2, so that the liquids may flow directly and smoothly into the separator, the gases and uncondensed vapors flowing along with them. The discharge of pipe 25 into the separator is through an opening 27 having 110 an associated deflector 27^a so that all the liquids, gases and vapors are discharged tangentially along the inner surface of the cylindrical wall of the separator and are 115 put into a whirling motion around that wall. The separator inlet 27 is near the upper end of the cylindrical separator shell, and the liquids as they whirl also move toward the bottom. By reason of difference in specific gravities, the liquids go to the outside against the cylindrical wall while the gases go to the inside; and the gases are constantly being passed through a screen wall 28 located in the center of the separator. This screen wall is formed by wrapping several convolutions of screen around the nipple or other cylinder 29 that has slots 30, this 120 nipple or cylinder being mounted on and 125 130

communicating with a gas and vapor exit pipe 31 that leads out from the top of separator 26. The screen wall 28 preferably does not extend to the bottom of the separator shell so that the bottom is left open for accumulation of liquid which then passes out through final liquid outlet 32.

It will be observed that the body of gases, vapors and liquids that is passed from header 15 to the separator is subjected to as little agitation as possible. Where the fluids pass through pipe 25 and come to inlet 27, the liquids are, of course, at that point on the bottom, while the gases and uncondensed vapors are above. But immediately upon being thrown into circular motion the liquids are thrown in a body to the outside while the gases and uncondensed vapors are thrown in a body to the inside. Whatever mist or finely divided liquid particles the gases and vapors may carry are also mechanically thrown to the outside into the body of liquid; and the screen wall, preferably formed of a number of layers of relatively fine mesh screen, also gathers and separates any mist that may be present in the gases and vapors passing to the outlet pipe 31. The mist particles accumulating upon the screen flow down the screen into the body of liquid at the bottom of the separator. As a consequence, the gases and vapors finally emerging from the separator are cleaned of all liquids condensable at the lowest temperature maintained in the apparatus. For the purpose of maintaining a uniform temperature, thermometers may be installed in the upper part of the separator at T; and these may well be in the form of thermo-couples from which wires 35 (see Fig. 2) may run to an indicating instrument.

I claim:

1. In a dephlegmator, a relatively long and shallow pan having a central partition

extending from one end to a point somewhat short of its other end, headers in the first mentioned end of the pan at opposite sides of the partition, a plurality of circulation pipes extending from one header the length of the pan, crossing the end of the pan and extending back the length of the pan to the other header, the pan being arranged horizontally and the pipes extending horizontally from one header to the other, means to introduce vapors to one header, means to remove vapors and condensate from the other header, and means to introduce cooling liquid to the pan at a point near the second mentioned header to flow toward the other end of the pan on one side of the partition and then back toward the first mentioned end of the pan on the opposite side of the partition, and a separator embodying a vertical tubular shell with a tangential opening near its upper end communicating with the second mentioned header, and a gas and vapor outlet at the center of the shell, said gas and vapor outlet embodying a central slotted pipe with a surrounding screen wall composed of a plurality of layers of screen. 70

2. In a dephlegmator, a relatively long and shallow pan adapted to contain a cooling liquid, vapor circulating pipes arranged substantially horizontally in the pan and adapted to be covered by cooling liquid, 75 means to introduce vapors to said pipes at one end, an outlet leading horizontally from the other ends of the pipes, a separator embodying a vertical tubular shell with a tangential inlet near its upper end communicating directly with said outlet, a central outlet for gases and vapors in the shell, and an outlet for liquid at the lower part of the shell.

In witness that I claim the foregoing I have hereunto subscribed my name this 10th day of July, 1925.

JULIAN A. CAMPBELL.
